UNITED STATES PATENT OFFICE.

SAMUEL WILLIAMS, OF TOLEDO, OHIO.

AUTOMOBILE-RADIATOR.

1,233,429.

Specification of Letters Patent. Patented July 17, 1917.

Application filed May 8, 1916. Serial No. 96,141.

To all whom it may concern:

Be it known that I, SAMUEL WILLIAMS, a citizen of the United States, and a resident of Toledo, in the county of Lucas and State of Ohio, have invented a certain new and useful Automobile-Radiator; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to radiators, and particularly to those of the type adapted for use on automobiles in connection with the water cooling systems of the internal combustion engines thereof.

The object of my invention is the provision of an improved radiator of the class described, which is simple and inexpensive in its construction and has each tier or section of air cells thereof formed by a single strip or sheet of metal, whereby the assembling of the parts of a radiator is materially facilitated and simplified and the making of repairs rendered easier.

The invention is fully described in the following specification, and while, in its broader aspect, it is capable of embodiment in numerous forms, a preferred embodiment thereof is illustrated in the accompanying drawings, in which—

Figure 1 is a front elevation of a radiator embodying the invention. Fig. 2 is an enlarged perspective view of one of the air cell sections of the radiator, with a part broken away. Fig. 3 is an edge view of two air cell sections placed together to form a water circulating passage therebetween, and Fig. 4 is a section on the line 4—4 in Fig. 3.

The radiator embodying my invention is composed of a plurality of air cell sections A, which are secured together in side abutting relation and inclosed within a casing B, which casing has water chambers at the top and bottom thereof with which the upper and lower ends of the water passages between the cell sections A respectively communicate, as is well understood in the art.

Each cell section A forms a plurality of horizontally disposed cells a, which extend from front to rear of the radiator. Each cell section A is composed of a single sheet or strip of sheet metal, such metal being so bent as to form the successive cells of a section in superimposed relation. Beginning, in the present instance, at the upper end of a cell section, the metal sheet or strip forming the same is bent in inverted U-shape to form the leg portions 1 and 2 and crown portion 3, with the leg portion 1 slightly longer than the depth of the first cell a so as to lap the adjacent edge of the next subjacent cell a, as shown at 4. The leg 2 is of sufficient length to extend down beyond the adjacent side of the second cell and to lap for a short distance the respective upper edge of the third cell in order. The metal is then again formed in U-shape with the right-hand leg 5 thereof, or that adjacent to the leg 2, doubled back within said leg in close side abutting relation thereto, and with its other or left-hand leg 6 extending down below the adjacent upper edge of the fourth cell in order, while the crown portion 7 of such U-shaped part forms the bottom and top, respectively, of the upper and second cells of the section. The sheet is then again formed in U-shape, with its left-hand leg doubling back against the inner side of the leg 6 for substantially half the length thereof, and with its other leg, which is the long leg, extending down in lapping relation to the adjacent upper edge of the fifth cell in order, and this operation is repeated as many times as there are cells in the section until the last section is reached, which is formed by bending the extended end portion of the long side leg of the cell across the section to form the bottom wall of the bottom cell and to abut at its end against the opposite doubled back wall portion of the cell, as shown at 95 the bottom of Fig. 2. In other words, a radiator section A comprises a plurality of integrally connected U-shaped parts which are nested in successive order one within another, with their crown portions equidistantly spaced in accordance with the desired depth of the cells, and with one leg of each

U-shaped part lengthened with respect to the other leg and integrally connected at its free end to the free end of the short leg of the U-shaped part nested therein, the long legs of the successive U-shaped parts alternating with respect to the sides of the section. The short leg of each U-shaped part laps for a short distance the inner end portion of the long leg of the next U-shaped part in order, or the one nested therein, and is fixedly secured thereto in a water tight manner by solder, or other suitable means.

It is evident with this construction of radiator section that it is formed of a single strip of sheet metal and that alternate side walls of the successive cells are of double thickness by reason of the doubling back of the metal at such sides.

The sections A have their sides inwardly bowed or broadened at their outer ends so that the broadened end portions of adjoining sections abut and space the intermediate portions of the sections to form a vertical water space or passage 8 therebetween. 25 When the sections A forming a radiator are secured together in block form the front and rear sides of the block are dipped in solder, or otherwise suitably treated to secure the sections together and to close any spaces 30 occurring between the abutting edge portions of the sections to render the passages 8 water tight at such edges.

When the sections are assembled it is preferable, but not necessary, to place the 35 double-thickness or reinforced side wall of the cells in each section opposite the single-thickness side walls of the cells of the adjoining section, as shown in Figs. 3 and 4. It is also preferable in assembling to have 40 the leg portions of the respective U parts of the sections extending downward instead of upward, thereby lessening the tendency of leakage through the seams 9 of the sections.

I wish it understood that my invention 45 is not limited to any specific construction, arrangement or form of the parts, as it is capable of numerous modifications without departing from the spirit of the claims.

Having thus described my invention, what 50 I claim as new, and desire to secure by Letters Patent, is—

1. In a radiator, a plurality of U-shaped sheet metal parts nested together to form a plurality of cells and having their legs extending in the same direction, the crown portions of said parts being spaced and the legs of each part being secured to the sides of the part nested therein.

2. In a radiator, a plurality of U-shaped 60 sheet metal parts nested together to form a plurality of cells, the crown portions of said parts being spaced, and each part having one leg integrally connected to the leg of the next part in order.

65 3. In a radiator, a cell section having a

plurality of cells formed of a single piece of sheet metal which is bent to form successive U-shaped parts nested one within another, with their crown portions spaced lengthwise of the section and with alternate 70 legs of the successive parts integrally connected to the adjacent leg of the next part in order.

4. In a radiator, a plurality of U-shaped sheet metal parts nested together to form a plurality of cells vertically of the radiator, the crown portions of said parts being spaced, and the legs of each part being of unequal length, with the long leg integrally connected to the short leg of the next part 75 in order.

5. In a radiator, a plurality of U-shaped sheet metal parts nested together to form a plurality of cells, the crown portions of said parts being spaced, and the legs of each part 85 being of unequal length, with the long legs thereof alternating with respect to the sides of the section and each attached to and co-operating with the short leg of the next section in order to form the side wall of a cell. 90

6. In a radiator, a plurality of U-shaped sheet metal parts nested together to form a plurality of cells, the crown portions of said parts being spaced, and the legs of each part being of unequal length, with the long legs 95 of the several parts alternating with respect to the section sides and integrally connected at their outer ends to the outer ends of the short legs of the parts next in order, the connected ends of the long and short legs of adjoining parts being fixed to the adjacent edge of the crown portion of an adjoining section.

7. In a radiator, a plurality of U-shaped sheet metal parts nested together to form a 105 plurality of cells, the crown portions of said parts being spaced, and the leg portions thereof being alternately lengthened, with the long leg of one part laps the short leg of the next part in order and integrally connected to the end of said short leg, with the adjacent end portions of said legs laps the end of the long leg of the third part in order and forming a close joint therewith.

8. In a radiator, a plurality of sections disposed side by side and forming a water passage therebetween, each of said sections having a plurality of U-shaped parts forming successive cells, with the crown portions 110 of said parts spaced, and with the legs thereof alternately lengthened to extend down at the outer side of the short leg of the next part in order and attached at its end to the end of the short leg which it laps and to the 125 end of the third U-shaped part in order.

9. In a radiator, a plurality of cell sections disposed side by side and forming water passages therebetween, each section having a plurality of U-shaped parts nested 130

together to form cells, with their crown portions vertically spaced and with alternate legs lengthened and secured at their ends to the ends of the short legs of adjoining sections, the long legs forming the side walls of the two adjoining cells, and the short legs coöoperating with the long legs each to

form the side walls of one cell, the ends of the connected long and short legs being attached to and forming a close joint with the 10 end of the adjacent U-shaped part.

In testimony whereof, I have hereunto signed my name to this specification.

SAMUEL WILLIAMS.
